G. MAROTTA,
SPARK PLUG,
APPLICATION FILED SEPT. 2, 1920.

1,415,668.

Patented May 9, 1922.

Inventor:
Gabriel Marotta
By his attorney
Pierre Barnes

UNITED STATES PATENT OFFICE.

GABRIEL MAROTTA, OF SEATTLE, WASHINGTON, ASSIGNOR OF ONE-HALF TO ABRAM VAN AALST, OF SEATTLE, WASHINGTON.

SPARK PLUG.

1,415,668.

Specification of Letters Patent.

Patented May 9, 1922.

Application filed September 2, 1920. Serial No. 407,781.

To all whom it may concern:

Be it known that I, GABRIEL MAROTTA, a citizen of the United States, residing at Seattle, in the county of King and State of Washington, have invented certain new and useful Improvements in Spark Plugs, of which the following is a specification.

This invention relates to improvements in spark plugs for internal combustion engines and the object of my improvements is to provide a spark plug having a plurality of terminals on the end thereof that are arranged in such a manner as to make it necessary for a spark to leap a plurality of gaps before reaching the grounded side of the circuit thereby affording a multiple spark for the purpose of insuring ignition and eliminating liability of short circuiting of the plug by carbonizing.

Another object is to provide a plug of this character which is of strong and simple construction, inexpensive to manufacture, efficient in operation and obviating either a leakage of gas or a leakage of electrical current.

With the above and other objects in view as will appear from the following description, the invention consists in the novel construction, adaptation and combination of parts as will be hereinafter described and claimed.

In the accompanying drawings, Figure 1 is a view in vertical mid-section of a spark plug constructed in accordance with this invention, and Fig. 2 is a plan view of the bottom end of the plug.

Like reference numerals designate like parts throughout the several views.

Referring to the drawings, the numeral 5 designates a tubular metal shell or body which adjacent to its lower end is threaded as at 6 to adapt it to be screwed into an opening therefor in an engine cylinder and above such threaded portion said body is desirably provided with a polygonal wrench engageable portion 7.

Extending axially through the shell 5 is a sleeve 8 of porcelain, or an equivalent insulating material having a head 9 at its lower end provided with a convex extremity 11 and affording an annular shoulder 10 above the head.

The sleeve 8 is of less diameter than the opening 12 therefor in the shell 5 to provide an annular air space about the sleeve.

The upper end of the sleeve 8 extends above the upper end of the shell and into a recess of a cap 13 of insulating material, such as conventionally known as fibre. Above the sleeve said recess affords an air space 14. The cap 13 rests upon the top of the shell 5 and is provided on its lower end with an extension 15 which serves as a bushing between the upper end of the shell and the sleeve 8 to thereby securely hold the latter in spaced relation with the shell.

The head 9 is surrounded by a packing 16 of insulating material as asbestos and which, in turn, is enclosed within a copper jacket 17. The copper jacket 17 fits snugly within the enlarged bore at the lower end of the shell 5 and against an annular shoulder 18.

The lower portion of the shell 5 preferably tapers as at 20 and the extreme bottom edge of such shell is bent or crimped under the end of the head 9 as at 21 to thereby retain the sleeve within the shell 5.

The sleeve and cap 13 are centrally bored for the reception of an electrode 22 having a relatively small head 23 at its lower end and having its top end threaded for the reception of nuts 24 and 25 between which an electric circuit wire 26 may be secured. A washer 27 may be interposed between the nut 25 and cap 13.

Secured in the lower end of the sleeve head 9 and protruding below the same is a plurality of metal posts 28.

These posts serve as insulated conductors so that a current from the head 23 of the electrode 22 by jumping across the gaps from post to post may reach the shell 5 and be grounded.

In thus jumping from post to post, the current is divided with the production of a plurality of sparks which ordinarily follow the lines of least resistance with paths in different directions from the head 23 of the electrode 22 in travelling among the posts 28 toward the grounding shell 5.

In the plug shown in the drawings it will be obvious that by pursuing the shortest possible route from the central electrode 22 to the shell 5 the igniting current will be compelled to jump a number of gaps with a corresponding number of sparks and that at each time a current branches from the most direct route additional sparks will be produced.

Should carbon collect on the posts 28 or

the terminal head 23 in sufficient quantities to form a short circuit between any two of them there will remain several gaps that a spark must jump before reaching the ground 5 terminal or shell 5 and the plug therefore cannot be completely short circuited by carbon unless sufficient carbon is deposited to form a continuous bridge between the terminal head 23 and the shell.

10 The foregoing description taken with the accompanying drawings discloses what is now considered the preferred form of my invention, but it will be understood that such changes as are within the scope of the following claim may be resorted to without departing from the spirit of the invention or sacrificing its advantages.

What I claim, is,—

20 A spark plug comprising a metal shell provided with a central opening with an enlarged lower portion to afford a shoulder, a sleeve of insulating material of less diameter than said opening extending lengthwise therethrough, said sleeve having a head 25 of relatively large diameter disposed within

the enlarged lower portion of the shell opening, and spaced from the walls thereof, said head having a convex extremity, insulating material surrounding said head, a copper jacket enclosing said insulating material the 30 lower edge of said copper jacket and the lower edge of said shell being bent over the edge of said head, a cap of insulating material arranged to seat on said shell and having an annular projection extending into the 35 annular space between said shell and said sleeve, an electrode extending lengthwise through said sleeve, the lower end of said electrode protruding a short distance from the center of said head, and a plurality of 40 metal posts embedded in said head in spaced relations between said central electrode and said shell.

Signed at Seattle, Washington, this 25th day of August 1920.

GABRIEL MAROTTA.
